COMBINED DRAWER PULL AND BACK PLATE THEREFOR

Emil J. Bocade, Grand Rapids, Mich., assignor to Keeler
Brass Company, Grand Rapids, Mich., a corporation of
Michigan

Filed Aug. 6, 1968, Ser. No. 13,043

Term of patent 14 years

Int. Cl. D8—03

U.S. Cl. D8—158

FIG. 1.

FIG. 2.

FIG. 3.

FIG. 4.

FIG. 5.

FIG. 6.

FIG. 1 is a front elevational view of the combined drawer pull and back plate showing a first embodiment of my new design;

FIG. 2 is a side elevational view of the combined drawer pull and back plate shown in FIG. 1;

FIG. 3 is a sectional view taken along lines 3-3 of FIG. 1;

FIG. 4 is a front elevational view of a combined drawer pull and back plate illustrating a second embodiment of my invention;

FIG. 5 is a right side elevational view of the combined drawer pull and back plate shown in FIG. 4, the opposite side being identical;

FIG. 6 is a sectional view of the drawer pull taken along lines 6-6 of FIG. 4.

I claim:

The ornamental design for a combined drawer pull and back plate therefor, as shown and described.
